UNITED STATES PATENT OFFICE

145,545

DESIGN FOR AN AIRPLANE

Enrique R. Thompson, El Paso, Tex.

Application May 29, 1945, Serial No. 119,795

Term of patent 3½ years

(Cl. D71—1)

To all whom it may concern:

Be it known that I, Enrique R. Thompson, a citizen of the United States, residing at El Paso, in the county of El Paso and State of Texas, have invented a new, original, and ornamental Design for an Airplane, of which the following is a specification, reference being had to the accompanying drawings, forming a part thereof.

Figure 1 is a top perspective view of an airplane

showing my new design as it appears with the landing gear retracted as in flight.

Figure 2 is a front elevational view.

Figure 3 is a side elevational view thereof.

I claim:

The ornamental design for an airplane, as shown.

ENRIQUE R. THOMPSON.
